CLAIM

The ornamental design for a breath sensing device, as shown and described.

DESCRIPTION

FIG. 1 is an isometric view of a breath sensing device in accordance with the present invention, showing the device with its pivoting lid in a closed position.

FIG. 2 is an isometric view of the breath sensing device of FIG. 1, showing the device with its pivoting lid in an open position.

FIG. 3 is a front view of the breath sensing device of FIG. 1, showing the device with its pivoting lid in a closed position. The back view is a mirror image of the front view. FIG. 4 is a front view of the breath sensing device of FIG. 1, showing the device with its pivoting lid in an open position.

FIG. 5 is a right side view of the breath sensing device of FIG. 1, showing the device with its pivoting lid in a closed position. The left side view is similar to the right side view. FIG. 6 is a right side view of the breath sensing device of FIG. 1, showing the device with its pivoting lid in an open position.

FIG. 7 is a top view of the breath sensing device of FIG. 1, showing the device with its pivoting lid in a closed position. FIG. 8 is a top view of the breath sensing device of FIG. 1, showing the device with its pivoting lid in an open position; and,

FIG. 9 is a bottom view of the breath sensing device of FIG. 1, showing the device with its pivoting lid in a closed position.

Any broken lines are for illustrative purposes only. None of the broken lines form a part of the claimed design.

1 Claim, 6 Drawing Sheets
